UNITED STATES PATENT OFFICE.

SAMUEL S. RIEGEL, OF SCRANTON, PENNSYLVANIA, ASSIGNOR TO PATTERSON-ALLEN
ENGINEERING COMPANY, A CORPORATION OF NEW YORK.

TENDER-TANK VALVE.

1,143,726.

Specification of Letters Patent. Patented June 22, 1915.

Application filed December 26, 1913. Serial No. 808,738.

To all whom it may concern:

Be it known that I, SAMUEL S. RIEGEL, citizen of the United States, and resident of Scranton, county of Lackawanna, and State 5 of Pennsylvania, have invented an Improvement in Tender-Tank Valves, of which the following is a specification.

The object of my invention is to provide a construction of valve which shall be specially suitable for tanks of locomotive tenders and employed for controlling the supply of water to the injector which delivers the feed water to the boiler.

More specifically, my object is to so construct my improved valve that it shall embody simplicity and durability; that it shall be quick acting and provide a direct flow for the water; that it shall provide a drainage pocket or well below the tank and above 15 the valve controlled port and so constructed that it is adapted for attachment below the bottom of the tank; that it may be operated by a single movement of a lever arm and locked in open or closed positions; and that 20 it shall constitute a positive shut off valve to the water flowing toward the outlet and a check valve to the flow of the water in the opposite direction, whereby the boiler pressure may be employed for blowing the 25 water from the hose connection back through the valve into the tank to avoid damage due to freezing of the water in the 30 hose and associated metal connections.

My invention consists of certain features 35 of construction whereby each and all of the above recited objects may be secured, the said several features of construction being fully described hereinafter and more particularly defined in the claims.

40 My invention will be better understood by reference to the drawings, in which:—

Figure 1 is a side elevation of a portion of a locomotive and its tender with my improved valve device and connections applied thereto; Fig. 2 is a plan view of my improved valve with its top plate removed; Fig. 3 is a sectional elevation of the valve taken on line $y-y$ of Fig. 1; Fig. 4 is a sectional elevation of the same taken on line 45 $x-x$ of Fig. 2; Fig. 5 is a plan view of the locking detent plate removed from the spindle; and Fig. 6 is a plan view of the abutment and guide plate removed from the valve casing.

50 2 is the locomotive and 3 its tender pro-

vided with the usual water tank. Secured to the bottom plate 3^a of the tender tank (Figs. 1 and 3), is my improved valve 6. The water from the tank is fed to the hose 7 under the control of the valve and by said 60 hose is delivered to the injector 5, which delivers it into the boiler in the usual manner. The valve 6 is provided with an operating lever 10, which extends just below the sills of the tender body (Fig. 1), whereby the 65 control of the valve may be easily had for shutting off or turning on the supply of water. A screen 6^a may be employed above the valve (Fig. 3).

Referring now more particularly to the 70 valve *per se*, 11 is a cylindrical body having a flange 16 at the top, by which it is secured by bolts 17 to the bottom sheet 3^a of the tender tank, the cylindrical body forming a well or pocket below the bottom of the tank and 75 opening into the tank by a large aperture 3^c (Fig. 3) of approximately the diameter of the interior of the body. The body 11 has, at its lower portion, a transverse valve seat 12 having a thoroughfare 13 opening 80 into a chamber 14 below the seat and provided with an obliquely arranged outlet nipple 15 to which the hose coupling connects. The upper portion of the interior 85 wall of the body is formed with an annular shoulder 28, upon which a flange 29 of a plate 27 seats and to which it is clamped by the clamping screws 30^a extending through apertures in the plate and screwed into the body. The bottom surface of this 90 plate 27 is flat and acts as an abutment or thrust plate for the spring 26 of the spindle and for the swinging arm 24 for the valve piece 30; and moreover, this plate is provided with one or more apertures 27^a for 95 passage of water and preferably, one of these apertures is in direct alinement with the valve seat thoroughfare 13. The general construction of this plate 27 will be fully understood by reference to Figs. 3, 4 and 6. 100

The valve seat 12 is oblong and the opening or thoroughfare 13 is arranged at one end so as to leave room at the other end for the valve piece when moved transversely to open the valve (Fig. 2). This thoroughfare 105 13 may be bored through a solid seat surface and in this way the valve may be made "right" or "left" handed as desired, the chamber 14 below the seat being also oblong to include either of such openings.

Arranged to one side of the valve seat is a spindle bearing 18, in which the valve operating spindle 19 is journaled. This spindle 19 has, on its inner end, a circular collar 20 and a polygonal-shaped part 23. The collar 20 fits into a recess 22 which contains packing rings 21 of copper or other ductile metal surrounding the spindle 19 and presses upon said rings to form a water-tight joint. In place of these metal rings, other forms of packing may be employed where water is to be controlled. The inner end of the spindle is formed with a socket 25 in which a coiled spring 26 is placed, said 10 spring pressing against the plate 27 and causing the collar 20 to press down tightly upon the packing rings. The lower end of the spindle 19 is fitted with a lever 10 by which to rock it when actuating the valve piece 30.

24 is a swinging arm having a polygonal aperture through which fits the polygonal end 23 of the spindle and by which the arm is given a swinging motion within the valve body. The free end of the arm 24, on its side facing the valve seat 12, is provided with an annular recess 32 and a central hub 34. A valve piece 30, preferably circular in shape, rests upon the valve seat and has an 20 annular cylindrical flange 31 which telescopes with the recess 32 of the swinging arm, said connection acting to cause the valve piece to be moved with the arm and thereby caused to traverse the valve seat. 30 A spring 33 is arranged within the recess 32 of the arm 24 and presses upon the valve piece to force it upon its seat and at the same time force the arm against the under surface of the plate 27, as will be readily 35 understood by reference to Fig. 4. The space between the valve piece 30 and the central hub 34 on the arm 24 is sufficient to allow the said valve piece to be forced upward from its seat by a superior under or 40 back pressure, when desired, so as to act as a check valve. I have shown the preferred manner of connecting the valve piece with the swinging arm, which permits a perfect sliding fit at small cost, but I do not restrict 45 myself to the details shown, as any other suitable connection may be employed so long as the valve piece is moved with the arm and may act as a check valve.

By oscillating the arm or lever 10, the 50 spindle 19 is rocked and the arm 24 oscillated for the purpose of shifting the valve piece 30 over the valve seat 12, and opening or closing the thoroughfare orifice 13. A suitable locking means may be provided for 55 holding the spindle in its extreme positions of oscillation, the means shown consisting of a plate 35 fitted to the spindle so as to oscillate with it and having notches as 36 and 37, combined with a pivoted lock 38 hinged 60 to the case 11 and adapted for engagement

with the notches 36 and 37 according to the position to be assumed by the valve piece. For example, when the valve is closed the parts are as indicated in Figs. 2 and 4, and the lock 38 engages the notch 37 of the plate 70 35; and when the valve is in open position, the lock 38 engages the notch 36 of said plate 35.

From the foregoing description, it will be seen that the construction and assemblage 75 of the valve structure is very simple and inexpensive; and from the nature of the construction, the sliding valve piece will insure a tight fit with the valve seat because the parts have a regrinding effect by the natural 80 operation of the valve piece over its seat. The plate 27 is perforated or so shaped as to permit free passage of water to the interior of the body and ready access to the thoroughfare 13 when uncovered. By unpinning the lever or arm 10 and the locking plate 35 and also removing the plate 27, the entire valve structure may be readily dismantled for cleaning or repairs.

As the body 11 is arranged directly upon the bottom of the tank and projecting below the same, it acts as a pocket or well for draining the tank completely, and by removing the hose, the tank may, from time to time, be flushed out through the valve to 95 keep it in a clean condition, especially in those cases where the feed water is impure and sediment settles from it in the tank.

Where the water is allowed to remain in the hose 7 during cold weather and when the 100 locomotive is out of commission, there being no way for draining said hose and its connections, the water is liable to freeze and much damage has heretofore been caused in this manner. My improved valve enables 105 the water in the hose to be blown back through the valve into the tank, when the locomotive is run into the round house or into the yard over night. To accomplish this, the locomotive may be provided with 110 a by-pass pipe 8, provided with a hand valve 9 for turning steam into the hose 7 and blowing the water therein through the valve into the tank. When this superior steam pressure is applied to the discharge side of 115 the valve, it forces the valve piece 30 upward away from its seat and permits the upward flow of the water. The spring 33 is compressed until the valve piece 30 is brought against the hub or stop 34 of the 120 arm 24 and during the action of the valve as a check-valve; and as soon as the steam is shut off the spring quickly forces the valve piece upon its seat and prevents the return 125 of the water. In this way, the hose is kept clear of water when the weather conditions make it desirable, but at all other times the water may be permitted to remain in the hose as heretofore. In many forms of injectors in general use the steam may be 130

permitted to blow back through the hose before the injector is adjusted to force the water into the boiler and in such cases the by-pass pipe 8 and valve 9 may be omitted 5 and the injector alone relied upon.

I have shown the general construction and details of my improved valve device in the form I have found most desirable in commercial practice, but I do not wish to restrict myself thereto, as the details may be varied within reasonable limits without departing from the spirit of the invention defined in the claims.

In this application I make no claim to the 15 system comprising the use of the above described valve in connection with the locomotive and tender whereby the steam pressure of the locomotive may be employed to blow the water from the hose connection 20 back through the valve into the tender tank, utilizing the valve as a check valve when it is desired to clear the hose of water in the winter time, as said system and combination of parts forms subject matter of a divisional 25 application filed May 8, 1914, and Ser. No. 837,123.

Having now described my invention, what I claim as new and desire to secure by Letters Patent, is:—

30 1. In a device of the character stated, the combination of a body adapted to form a closure for an opening in the bottom of a tank, said body having an open top portion adapted for alinement with the tank opening, a discharge opening in its bottom portion 35 and an intermediate diaphragm portion having a port and valve seat, an abutment plate removably secured within said body below the top opening therein and provided with a normally open port for the 40 passage of fluid and having a guide surface arranged in parallel relation to the valve seat on the diaphragm, a spindle journaled in the body to one side of said valve seat 45 and extending exterior of said body and provided with a collar, an operating lever secured to said spindle, packing encircling said spindle and upon which the collar seats, an arm connected to said spindle to oscillate 50 therewith and free to move axially of said spindle, a valve piece movably mounted in the free end of said arm and guided over the valve seat, spring means located between said abutment plate and said spindle for 55 holding said collar seated upon said packing, and a spring between said valve piece and said arm whereby the arm is held and guided against said abutment plate and the valve piece is held against said valve seat with provision for acting as a check valve. 60

2. In a device of the character stated, the combination of a body adapted to form a closure for an opening in the bottom of a tank, said body having an open top portion 65 adapted for alinement with the tank open-

ing, a discharge opening in its bottom portion and a valve port and seat interposed between the open top and bottom portions, an abutment plate removably secured within said body below the top opening therein 70 and provided with a normally open port for the passage of fluid and having a guide surface arranged in parallel relation to the valve seat surface of the body, a spindle journaled in the body to one side of said seat 75 and extending exterior of said body, an operating lever secured to said spindle for rocking it, an arm connected to said spindle to oscillate therewith and free to move axially of said spindle to be guided by the abutment plate, a valve piece movably mounted in the free end of said arm, a spring between said valve piece and said arm whereby the arm is held against said abutment plate and the valve piece is held against said valve seat 80 with provision for acting as a check valve, and a manually controlled locking device for locking said spindle in each of its extreme positions of adjustment.

3. In a device of the character stated, the 90 combination of a body adapted to form a closure for an opening in the bottom of a tank, said body having a large opening at its top portion to form a well adapted to come into alinement with the tank opening, 95 a discharge opening in its bottom portion and a valve seat and port between said discharge opening and said well, an abutment and guide plate removably secured within said well portion of the body below the top 100 opening therein and provided with a normally open port or opening for the passage of fluid, a valve seated upon the valve seat and guided by the abutment plate, a spring to normally hold the valve upon its seat 105 whereby said valve is held against said valve seat with provision for acting as a check valve, a spindle journaled in the body and extending exterior of said body, an operating lever secured to said spindle for rocking it to open or close the valve, and means within the valve body movable with said spindle and adapted to oscillate therewith about its axis to move the valve. 110

4. In a valve, a body open at its top to 115 form a well and having a valve seat and thoroughfare through the same and terminating in an outlet port at its bottom, combined with a spindle journaled in the body to one side of the valve seat and extending 120 through the bottom of the body, a swinging arm oscillated by the spindle and loosely connected therewith in an axial direction, a removable guide plate for holding the swinging arm in position arranged in the 125 open top portion of the body, a valve piece movable on the valve seat and connected with the swinging arm with capacity for free movement from the valve seat toward the arm to permit back flow through the 130

valve, a spring between the valve piece and the swinging arm whereby the swinging arm is pressed against the guide plate and valve piece is normally pressed upon the 5 valve seat but is also free to act as a check valve, and means for detachably holding the plate in position against the action of the spring.

5. In a valve, a cylindrical body open and 10 flanged at the top to provide a well and having at its lower part a valve seat provided with a thoroughfare terminating in an outlet, combined with a plate set down into the body below the flanged upper surface and 15 detachably clamped therein parallel to the valve seat said plate also providing apertures for normal free flow of fluid, a swing-

ing arm guided by the under surface of the plate, a valve piece guided by the swinging arm and movable over the valve seat, a 20 spring arranged between the valve piece and swinging arm for holding said parts respectively against their guiding surfaces and allowing the valve piece to act as a check valve, and means extending through the 25 body at the end opposite to the open flanged end for oscillating the swinging arm.

In testimony of which invention, I hereunto set my hand.

SAMUEL S. RIEGEL.
